US0D1084062S

(12) **United States Design Patent** (10) Patent No.: **US D1,084,062 S**
(45) Date of Patent: ** Jul. 15, 2025

(54) **CYLINDRICAL DIE FOR THREAD FORM ROLLING**

(71) Applicant: **FORM ROLL TECH CO., LTD.**, Yamanashi (JP)

(72) Inventors: **Toshinaka Shinbutsu**, Yamanashi (JP); **Shuichi Amano**, Yamanashi (JP)

(73) Assignee: **FORM ROLL TECH CO., LTD.**, Yamanashi (JP)

(**) Term: **15 Years**

(21) Appl. No.: **29/863,335**

(22) Filed: **Dec. 18, 2022**

Related U.S. Application Data

(62) Division of application No. 35/513,160, filed on Mar. 30, 2021 (U.S. filing date under 35 U.S.C. 384), and having an international filing date of Mar. 30, 2021, now Pat. No. Des. 989,824.

(57) **CLAIM**

The ornamental design for a cylindrical die for thread form rolling as shown and described.

DESCRIPTION

FIG. 1 is a perspective view of a cylindrical die for thread form rolling showing our new design;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof;

FIG. 8 is an enlarged perspective view of the portion 8-9 indicated in FIG. 1;

FIG. 9 is an enlarged front view of the portion 8-9 indicated in FIG. 1; and,

FIG. 10 is an enlarged top view of the portion 8-9 indicated in FIG. 1.

1 Claim, 6 Drawing Sheets
